UNITED STATES PATENT OFFICE.

HAROLD L. TUERS, OF NEW YORK, N. Y.

ENVELOPE.

Application filed August 20, 1920. Serial No. 404,819.

To all whom it may concern:

Be it known that I, HAROLD L. TUERS, a citizen of the United States, residing at New York, in the county of New York and State 5 of New York, have invented certain new and useful Improvements in Envelopes, of which the following is a full, clear, and exact description.

This invention relates to envelopes 10 adapted to receive phonograph records of the disk type; and it is an object of the invention to provide an envelope which will be equally suitable for either large or small size records or both. Briefly stated the invention consists in the provision of a record envelope having a plurality of record compartments or pockets each compartment being adapted for a given size record. The arrangement is preferably such that the 20 labels on the records are in front of the envelope window thus adding to the convenience of the envelope.

Other objects will appear in the claims and from the detailed description to the invention in connection with the accompanying drawings in which—

Fig. 1 is a plan view of the envelope;

Fig. 2 is a section taken on line 2—2 of Fig. 1;

Fig. 3 is a section taken on line 3—3 of Fig. 1;

Fig. 4 is a fragmentary view in plan of the bottom of the envelope showing an alternative manner of securing certain parts 35 shown in Fig. 1;

Fig. 5 is a view showing the lay-out of the sheet from which the envelope may be made; and

Fig. 6 shows the sheet partly folded.

Like reference characters designate like parts throughout the several views.

The envelope comprises two main walls 10 and 11 of different areas; and extending inwardly from the side edges of the larger 45 wall are wall-members 12 and 12' and likewise extending inwardly from the wall 11 are what, for the purpose of this application, I shall call guide-strips 13 and 13', the guide-strips and wall-members being joined 50 at their inner edges. It will now be seen that the walls are separated by bellow-like means which serve to divide the envelope into compartments or pockets for the reception of records.

The bottom of the envelope is closed by

what are in effect step-like means. These means comprise, in connection with the compartment of which the wall 11 is a part, a trough which is formed by a flap or member 14 secured to the lower edge of the wall 11 60 and projecting inwardly. The ends of this flap I prefer to arrange in the following manner: The inside edge of each of the bellows members, which comprise a wall member and guide-strip, is cut away at its 65 lower portion as shown at 15 (Fig. 5) to receive the ends of the flap 14 which are, as a consequence, straddled by said guide-strips and wall-members as more fully shown in Fig. 6. This arrangement makes 70 for a strong and substantial construction at the bottom of the envelope by reason of the fact that both sides of the straddled ends of the flap may, obviously, be united or secured to both the wall-member and guide-strip. The construction also makes for a perfectly smooth and unobstructed surface of the side of the wall-members and guide-strips that face the walls 10 and 11, respectively. 75

The closure for the compartment of which member 10 forms one wall, constitutes a flap or member 16 secured to the bottom edge and projecting inwardly. This flap may over-lie the lower part of the wall 11 80 as shown in Figs. 1 and 2 or it may be inserted between the walls 10 and 11 as shown in Fig. 4. When the flap 16 over-lies the wall 11 the bottom of the adjacent compartment wall is somewhat more protected than 85 is the case when it is placed next to the wall 10 as in Fig. 4; but in some respects a more satisfactory envelope results from the latter arrangement by reason of the fact that the intermediate portion of the flap 90 can then be secured to the flap 14. Both flaps 14 and 16 then serve as a unitary partition member between the walls 10 and 11. 95

In order that the envelopes may readily be assembled into a book such as an album, 100 I have provided a binding strip or extension 17 which projects from one side of the envelope (see Figs. 1 and 3). The provision of this member is of course entirely optional and in Fig. 4 such member is not 105 shown.

Referring now to Figs. 5 and 6 it will be seen that the envelope can be and preferably is made from a single sheet of flexible material, preferably paper. From these fig- 110

ures it will be seen that the sheet is laid out to provide main walls 10 and 11, the latter being of less area than the former. The adjacent sides of walls 10 and 11 are separated by a portion which goes to make up the wall-member 12' and the guide-strip 13', the lines of demarkation between the parts being defined by three parallel creases as shown by the dotted lines. The lower end of the middle crease ends at the apex of a cut-out V-shaped portion which results from cutting away a portion of the meeting edges of the guide-strip and wall-member to enable the ends of the flap 14 to be straddled thereby. The flap 14 and the flap 16 are preferably continuations of the bottom of the walls. The member 14 is shown as having a re-entrant portion 14' but this is purely optional. The other side edge of the wall 11 is continued to form the wall-member 12 and guide-strip 13 and when the envelope is to be provided with means for binding in an album the extension 17 is also provided. It will of course be understood that sufficient margin P is provided at the extremities of the sheet to allow suitable jointure to be made.

In folding the sheet into shape the material is first bent as shown in Fig. 6 to define the guide-strips and wall-members and the ends of the flap 14 inserted in the V-shaped or cut away portion 15 as will readily be understood. The folding of the envelope is then completed by turning the wall 10 over against the already folded portion and then turning the extension 17 on itself. The manner just described of folding the envelope is merely an example of a convenient way of doing it and is not to be taken as a limitation. After the parts have been folded into shape the flap 14, the flap 16, and the terminals P are secured to their respective contiguous members by any suitable means, preferably by some adhesive substance.

Prior to my invention it has not been possible to file records of different sizes in the same envelope and maintain the same in a definite relationship therein, more particularly to maintain the labels on the records in front of the windows afforded by the central circular opening or openings W in the envelope walls. My invention makes possible the filing of a small record in an envelope which is equally adapted for a larger size record and thereby obviates the necessity of providing different size envelopes for different size records. I have, in effect, provided two envelopes in one for different size records. The amount of material required in the making of my device is only slightly greater than that required for the making of a single envelope. This feature alone is of great value.

While I have described the envelope as

comprising walls 10, 11; guide-strips 13, 13'; wall-members 12, 12'; and the flaps 14, 16, it will be apparent that the envelope may be viewed as consisting of two walls 10, 11 which are secured to the respective sides of a flat U-shaped member, the wall-members 12, 12' forming the legs and the flap 14 forming the bottom of the U, or when the flap 16 is arranged as in Fig. 4 both said flaps forming the bottom thereof. The wall 10 is of course secured to the outside marginal edges of the U while the wall 11 being smaller than the wall 10 is secured between the inner and outer marginal edges of the U.

It will be readily appreciated that the envelope though preferably made from a single sheet of material may be fabricated from separate pieces and that the invention may be embodied in different forms without departing from the spirit of the invention. It is therefore to be understood that the detailed description and disclosure are to be taken as illustrative rather than as limitations of the invention, reference being had to the appended claims for the scope of the invention.

What I claim is:

1. The combination of means for holding disk records of different diameters in axial alignment comprising an envelope or bag having different-sized compartments.

2. A disk-record envelope comprising a plurality of walls, and means for dividing the envelope into a plurality of record compartments comprising bellows-like means between said walls.

3. An envelope comprising a pair of walls of different areas having windows therein, and means dividing the envelope into a plurality of compartments which are concentric with respect to said windows, said means comprising bellows-like members between said walls.

4. An envelope to accommodate different size records comprising a pair of walls having windows therein, means for maintaining the windows in concentric relation comprising bellows-like members between the walls at the sides thereof, and step-like abutments between the walls at the bottom of the envelope.

5. In a record envelope, a pair of rectangular walls having aligned windows, a flat U-shaped member separating said walls, the legs of said member being equidistant from said windows, the peripheral edge of one of said walls being secured to the outside marginal edge of said member, and the peripheral edge of the other wall being secured to said member outwardly of the inner marginal edge of said member.

6. In an envelope for holding disk records of different diameters in axial alignment, a wall, a flap extending inwardly from the

- bottom thereof, guide-strips projecting inwardly from the sides of said wall and having a portion overlying the said flap, wall-members secured to the inner edge of said 5 guide-strips and projecting outwardly, a portion of said wall-members underlying said flap and extending below the bottom edge of the wall, a second wall secured to the outer edge of said wall-members, and a 10 closure between the bottoms of the two said walls. 50
7. In an envelope for holding disk records, a rectangular wall, a guide-strip projecting inwardly from one end thereof, a wall-member secured to the inner edge of said strip and projecting outwardly, a flap secured to the bottom edge of said wall and projecting inwardly, a similar guide-strip and wall-member at the opposite end of said 15 wall and similarly arranged with respect to said flap, a second wall of larger area than the first secured to the outer edge of said wall-members, and a closure member for the 20 bottom of said second wall. 55
- 25 8. In an envelope for holding disk records, a rectangular wall, a guide strip secured to one side edge thereof and projecting inwardly, a flap secured to the bottom edge of said wall and projecting inwardly, the lateral portion of said flap underlying the lower portion of said strip, whereby a smooth unobstructed surface is had on the guide-strip facing said wall, a wall-member secured for 30 a portion of its length and projecting outwardly from the inner edge of said guide-strip, the unsecured portion of said wall-member underlying said flap whereby a wall surface unobstructed by said flap is had, a similar guide-strip and wall-member similarly arranged at the other side of said wall, 35 a second wall secured at its side edges to the outer edges of said wall-members, and a flap secured to the bottom edge of said second wall and projecting inwardly. 40
- 45 9. As an article of manufacture a sheet of bendable material having three parallel creases of different lengths between two main portions of said sheet that are adapted to serve as walls, the middle crease terminat- 50
- ing at the apex of a cut-out V-shaped portion, similar creases in the reverse order at one extremity of said sheet, a flap extending from the wall between two of said creases and separated from said wall by a crease intersecting the adjacent creases of the two groups of creases before mentioned, and a portion projecting from the other of said walls and separated from the body portion thereof by a crease running at right angles to the crease adjacent thereto. 55
10. Means for holding disk records of different diameters in axial alignment comprising an envelope or bag struck up from a single sheet of material and folded to form different sized compartments. 60
- 65 11. Means for holding disk records of different diameters in axial alignment comprising an envelope or bag having different sized compartments the walls of which are stepped one with respect to the other to facilitate the 70 insertion and removal of records.
12. Means for holding disk records of different diameters in axial alignment comprising an envelope or bag struck up from a single sheet of flexible material and 75 folded to form different sized compartments, the front and rear walls of each compartment not only being stepped with respect to each other, but also stepped with respect to the walls of any other compartment, 80 thereby facilitating the insertion and removal of records.
13. Means for holding disk records of different diameters in axial alignment comprising an envelope or bag struck up from a 85 single sheet of material and folded to form compartments, the size of each of which corresponds to the size of the records to be received by it.
14. Means for holding disk records of different diameters in axial alignment comprising an envelope or bag struck up from a single sheet of material and folded to form compartments of different sizes and opening in the same direction. 90
- 95 In testimony whereof, I affix my signature.

HAROLD L. TUERS.
